OPERATING HANDLE FOR MANUALLY
PROPELLED TOOLS

John J. McCabe, Cleveland, and Arthur W. Seyfried, Shaker Heights, Ohio, assignors to The Apex Electrical Manufacturing Company, Cleveland, Ohio, a corporation of Ohio

Application April 6, 1935, Serial No. 15,132

24 Claims. (Cl. 280—48)

This invention relates to floor cleaning tools and in particular floor tools employing an ambulant structure with an operating stick or handle pivoted thereto and extending therefrom.

5 Devices of the general type referred to, may comprise electric and non-electric suction cleaners; electric and non-electric carpet sweepers, as well as machines for scrubbing, sand-papering, polishing or otherwise treating floors. Such 10 devices ordinarily are in the form of a wheeled or caster-supported casing having pivoted thereto an elongated operating handle by means of which the device is propelled and steered over the surface being worked upon. The length of the operating handle makes it necessary to swing the same through a considerable arc to one side or the other in steering the device, and when working near a wall or an article of furniture, it is sometimes awkward or difficult to manipulate 15 the cleaner by reason of the fact that there is not sufficient room for the swinging of the handle.

One of the objects of this invention relates to the provision of an operating handle for devices of the type described, having an improved 20 means for steering the device by merely twisting the handle about its axis whereby the device may be directed into the corners and around objects on the surface being cleaned with a minimum of effort.

25 Other and further objects relate to the specific means and details of construction whereby the aforesaid object may be realized in a simple and inexpensive mechanism, including provisions for rendering the steering device inoperative so that the device may be used in much 30 the same manner as conventional handles for devices of the type referred to.

A further object of the invention relates to the provision of an improved handle stop or adjustment for the handles of devices of the type 35 described, which will facilitate raising the forward end of the device for clearing obstructions and which also serves to maintain the handle in either an upright or a horizontal position when 40 the device is not in use.

45 With these and other objects in view, the invention consists in the novel construction, arrangement and combination of parts, herein- 50 after illustrated and described in some of its embodiments in the accompanying drawings, and particularly pointed out in the appended claims.

The present invention constitutes a continuation-in-part of the invention shown in our co-pending application, Serial No. 678,454 filed June 55 30, 1933, for Suction sweeper.

In the drawings, Figure 1 is a perspective view of an electrically operated suction sweeper illustrating one of the various devices to which this invention may be applied; Figure 2 is an enlarged detail sectional view taken through the 5 axis of the lower part of the sweeper handle, illustrating the mechanism provided for steering the sweeper; Figure 3 is a detail view of the handle lock taken on Figure 2 in a direction indicated by line 3—3; Figure 4 is a plan view 10 of the underside of the handle bail with the plug cap of the motor cord removed, taken on line 4—4, Figure 2; Figure 5 is a detail sectional view taken on line 5—5, Figure 2; Figure 6 is an enlarged detail sectional view, illustrating 15 the structure associated with the ends of the handle bail; Figure 7 is a sectional view taken on line 7—7, Figure 6; Figure 8 is a sectional view similar to Figure 2, illustrating a modified form 20 of the invention; Figure 9 is a side elevational view, partly in section, of the structure shown in Figure 8; Figure 10 is a sectional view taken on line 10—10, Figure 8; Figure 11 is a sectional view taken on line 11—11, Figure 8; Figure 12 is a sectional view taken on line 12—12, Figure 25 8; Figure 13 is a detail view illustrating the handle lock; Figure 14 is a sectional view taken on line 14—14, Figure 13; and Figure 15 is a plan view of the sweeper illustrating the mode of operation of the steering handle. 30

The suction sweeper shown in Figure 1 was selected for the purpose of illustrating this invention, largely because devices of this kind are commonly used and well understood and they represent one of the wider fields for the use of 35 the invention. It will become apparent as this description proceeds, that the invention is not specifically limited in its use to suction sweepers and that it is also useful in connection with other devices, some of which have been mentioned 40 earlier in this description.

The suction sweeper comprises a casing 1 supported upon wheels or casters 1^a as is customary in devices of this character. A filter bag 2 connected by means of a spring 3 to a handle 4, 45 communicates with the discharge outlet 5 of the casing structure. A foot pedal 6 is provided for raising or lowering the casing structure with respect to its supporting casters and the surface upon which the sweeper is resting. The mechanism associated with the foot pedal for effecting the aforesaid object may be of the type illustrated in Friend Patent No. 1,448,397 issued March 13, 1923.

A motor (not shown) is located within the cas- 55

ing structure 1 and an electric cord 7 carried by the handle 4 is provided for connecting the motor to a source of current supply. A pistol grip 8 having a resilient knob 10 at its outer end 5 is secured to the end of the handle 4 remote from the casing. The operating member 11 of a suitable switch (not shown) is carried by the pistol grip in position where it may be readily manipulated by the thumb of the operator for the purpose of controlling the operation of the electric motor of the device.

The lower end of the handle 4 is attached to a bail 12, the ends of which project through slots 13 formed in the casing structure. The arms of 15 the bail may be in the form of metal stampings which may be secured by means of bolts 9 to laterally extending arms of a tubular or cylindrical member 27. The arms of the bail are secured to the casing 1 by means of pivot pins 14 so that the handle may be swung through a considerable arc about a horizontal axis. Rollers 15 are provided at the lower ends of the arms of the bail. These rollers are adapted for engagement with the bent-over ends 16 and 17 of a U-shaped 20 spring 18 fixedly attached at points intermediate 25 its ends to the casing structure by any suitable means, such as, rivets 20.

When the handle is moved to an upright position, the roller 15 rides over the bent-over end 30 16 of the spring and the handle is thus maintained in a vertical position. When the handle 4 is moved towards the floor, the roller 15 contacts with the end portion 17 of the spring and the resistance of the spring at this point is sufficient to permit raising of the forward end of 35 the nozzle by the handle for the purpose of lifting the end of the sweeper over slight obstructions. Further downward movement of the handle overcomes the tension of the spring, whereupon the handle may be adjusted to a substantially horizontal position, which may be advantageous under certain conditions as where the sweeper is used for cleaning under beds and other low objects, and when desired, the handle 40 may be returned to its original operating position upon overcoming the tension of the spring, which is accomplished without difficulty.

The handle 4 of the sweeper is rotatably joined to its bail 12 by means of a coupling enclosed 50 within an angularly bent section of tubing 21. The pivotal connection between the handle 4 and the bail 12 is provided for the purpose of changing the direction of movement of the sweeper by simply twisting the operating handle. This improvement is a great convenience in cleaning around articles of furniture and the like.

The lower end of the handle 4 is rotatably received in one end of the tubular fitting 21. The fitting 21 has a circumferentially disposed opening 60 at 22 defining a guideway for reception of the head of a screw 23 which is received in a fitting 24, fixedly secured to the end of the handle by means of such a screw. A second circumferential opening 25 is provided in the lower part of the tubular member 21 to define 65 a guideway for the head of a screw 26, threadably received in the cylindrical member 27 having laterally extending parts fixed to the arms of the bail 12, as previously described. The upper end of the member 27 is formed with gear teeth 70 28. The lower end of the fitting 24 carried by the handle 4 is also provided with a similar set of gear teeth 30.

The tubular member 21 is traversed at its bend 75 by a pin 31. A differential gear 32 is journaled

on the pin 31 within the tube 21. This gear meshes with the gear teeth 28 and 30, so that when the cleaner handle 4 is twisted in one direction, the member 27 which is rigid with the bail, is rotated in an opposite direction, and in this manner by a simple twist of the wrist, the direction of movement of the sweeper may be changed without swinging the sweeper handle through an arc to one side or the other, thereby saving the operator considerable labor in the use of the 10 sweeper, while at the same time facilitating its manipulation. The maximum arc through which the handle may be twisted is determined by the length of the slots 22 and 25, the ends of which are engaged by the heads of the screws 23 and 15 26 respectively at the extreme limits of the twisting movement of the handle. The use of the gears 28, 30 and 32 may be dispensed by fixedly attaching the handle 4 to the fitting 21 by any suitable means such as those illustrated in Figure 20 8, in which case, when the sweeper is being propelled, a twisting movement of the handle will turn the sweeper casing in the same direction as the handle is turned as will be described in detail presently.

A plate 33 is slidably mounted in a slot 34 formed in the fitting member 21, which is rigid with the bail 12. The plate 33 may be locked in its adjusted position by means of a winged screw 35 which extends through a slot 36 formed 30 in such member. The tube 21 has a slot 37 registering with the slot 34 when the handle is in a normal untwisted position. When the member 33 is moved into the slot 37, the sleeve 21 and the handle 4 are locked to the bail 12 and it is 35 then impossible to twist the cleaner handle with respect to the bail. This arrangement is provided for use when it is not intended or desired to use the steering device just described.

The electrical connections between the motor 40 and the switch of the sweeper are effected by conductors 38, 38 threaded through the handle 4. These conductors are connected at their lower ends to the element 40 of a separable plug connector. The plug element 40 is held in place by 45 means of a stamping 39 which is secured to the underside of the bail by bolts 9. The cooperating attachment plug cap, which is indicated by the numeral 41, is connected to an armored cable 42, which in turn is connected to the motor windings. The separable connection shown, is provided for the purpose of facilitating the disconnection of the handle from the device, and by providing a separable electrical connection at this point, the disconnection of the handle may 50 be effected without breaking any permanent or semi-permanent electrical connections. The plug element 40 has an annular shoulder 40^a received in a recess of complementary form in the member 21, and the outer face of the element is 55 formed with parallel sides which are gripped by the stamping 39, and in this manner, the plug element is held against movement in all directions.

In the modification of the invention shown in 65 Figures 8 to 14, the tubular handle 4 of the sweeper is fixedly secured to an angularly disposed tubular fitting 50, which is clamped to the end of the tube by means of a screw 51 received in spaced ears 50^a integral with the fitting. A suitable slot 53 is formed in the end of the tube for receiving a key 52 which is held on the screw 51 between oppositely disposed ears 50^a of the fitting 50. A tubular sleeve or gasket 54 may be interposed between the handle 4 and the fitting 50 for 70 75

insulating the handle from the sweeper casing. The lower end of the tubular fitting 50 is received within a tubular member 55, forming a part of the bail 12 as in the case of the element 21 previously described. The bail 12 of the device shown in Figures 8 to 14 is pivotally secured to the sweeper casing 1 in the manner illustrated in Figure 1. The element 55 at its upper end is inclined rearwardly of the bail. The lower end of the fitting 50 has a circumferentially disposed opening defining a guideway 56 as shown best in Figures 8 and 12 for receiving the reduced and unthreaded end of a screw 57 carried by the member 55. The rotatable connection just referred to permits the changing of direction of the sweeper upon the twisting of the sweeper handle, in much the same manner as for the mechanism previously referred to in connection with the discussion of the device shown in Figures 1 to 7.

In the present case, when the handle 4 of the sweeper is twisted about its axis, the lower end 58 of the angularly disposed fitting 50 is turned in the same direction, and at the same time this takes place, the position of the axis of the offset part of the member 55 is also similarly shifted, and by reason of such movement, the direction of movement of the sweeper is changed. Thus when the handle is twisted in a clockwise direction, a clockwise turning movement is imparted to the sweeper casing and contrarily for a reverse twisting of the handle.

The operation of the form of steering device first described is illustrated in Figure 15 in which the full lines indicate the normal position of the handle and its associated casing structure. When the hand grip 8 is twisted in a clockwise direction to the dotted line position shown in this figure, the casing 1 of the sweeper is shifted in a counterclockwise direction to the dotted line position shown. If the hand grip were twisted in a reverse direction, a corresponding reverse movement of the casing 1 would take place.

The member 55 is provided at one side with a slotted guideway 60 for slidably receiving a key 61 having an offset knob 62 for its operation. A portion of the key is undercut at its underside for receiving a bowed flat spring 63 which is provided for frictionally maintaining the key in its adjusted position. The key 61 is adapted for cooperation with a slot 64 formed in the member 50. The slot 64 and the guideway 60 are in alignment when the sweeper handle is in a normal untwisted position, and the relatively movable parts of the handle may be locked in such position by sliding the key 61 into registry with the slot 64 and conversely the handle parts may be unlocked by returning the key to the position shown in Figures 13 and 14.

In the use of the device, the pivoted connection between the handle bail 12 and the casing structure of the sweeper takes care of the movement of the handle bail about a horizontal axis as may be occasioned during the twisting movement of the handle for changing the direction of movement of the sweeper casing. The electrical connections from the handle switch to the motor of the sweeper are effected in substantially the same manner as previously described for the handle shown in Figure 1, the conductors 38 being connected to the separable plug element 40 which cooperates with the attachment plug cap 41 connected to the motor cable 42.

In the species of Figures 8 to 14, the steering 75 of the handle 4 is due to the Hooke's joint con-

nection in which 14 and 55, 58 are the pivots and the axis of 55, 58 is thus operative to steer the sweeper by reason of its horizontal component of movement. The vertical component of movement is taken care of by the pivotal connection 14 between the bail and the sweeper casing, and by reason of this joint, there is substantially no swinging of the handle and the steering movement is effected substantially entirely by a twisting movement of the handle.

In the species of Figures 1 to 7, the steering of the cleaner is effected by twisting the handle 4 and thus rotating the bail in the lower portion of the bent tube in a reverse direction through the action of the gears 28, 30 and 32.

In the handle shown in Figures 8 to 14, the lower ends of the conductors 38 are vulcanized to a strain relief in the form of a sleeve 65 having an enlarged end 66 carried in a cavity 67 of complementary form provided in the member 55. The interior of the member 55 is formed with an arcuate groove or slot 68 for receiving a projecting tongue 70 formed at the end of the fitting 50. The twisting movement which may be imparted to the sweeper handle is thus limited by contact of the tongue 70 with the ends of the groove 68. In both modifications of the invention the hand grip 8 is downwardly offset at an angle from the handle 4 so as to facilitate the twisting of the handle by utilizing the hand grip as a lever arm at this point.

Furthermore, it is to be understood that the particular forms of apparatus shown and described, and the particular procedure set forth are presented for purposes of illustration and explanation and that various modifications of said apparatus and procedure may be made without departure from the invention as defined in the appended claims.

Having thus described our invention what we claim is:

1. Means for directing a wheel supported, surface traversing implement comprising an elongated sectional handle member normally angularly inclined with respect to the implement and having freely operable couplings rotatably connecting said handle sections to each other and to the implement, the axis of one of said couplings extending substantially perpendicularly to the direction of motion of the implement and in a substantially horizontal plane, the axis of the other of said couplings being substantially normal to said first named axis and at an angle to the vertical, whereby a twisting motion of said handle member about its own axis produces a change in the direction of motion of the implement.

2. Means for manually propelling and directing a wheel supported, surface traversing implement comprising an elongated sectional handle member normally angularly inclined with respect to the implement and having freely operable couplings rotatably connecting said handle member sections to each other and to the implement, the axis of one of said couplings extending substantially perpendicularly to the direction of motion of the implement and in a substantially horizontal plane, the axis of the other of said couplings being spaced from and substantially normal to said first named axis and at an angle to the vertical, whereby a twisting motion of said handle member about its own axis produces a change in the direction of motion of the implement.

3. Means for manually propelling and directing a wheel supported, surface traversing implement comprising an elongated sectional handle member

- normally angularly inclined with respect to the implement and having a hand grip at the end remote from the implement, means for connecting one section of said handle member to the implement for movement about an axis extending substantially perpendicularly to the direction of motion of the implement and in a substantially horizontal plane, and means for connecting another section of said handle to said first named handle section for movement about an axis substantially normal to said first named axis and at an angle to the vertical, whereby a twisting motion of the hand grip of said handle member produces a change in the direction of motion of the implement.
4. Means for manually propelling and directing a wheel supported, surface traversing implement comprising an elongated handle member normally angularly inclined with respect to the implement and formed from two sections joined to each other for relative rotation, means for connecting said handle member to the implement for movement about an axis extending substantially perpendicularly to the direction of motion of the implement and in a substantially horizontal plane, the axis of the relative rotation of said handle sections being spaced from and substantially normal to said first named axis and at an angle to the vertical, whereby a twisting motion of the end of the handle remote from the implement about the axis of the handle in one direction or the other produces a corresponding change in the direction of motion of the implement.
5. Means for manually propelling and directing a surface traversing implement comprising an elongated handle member normally angularly inclined with respect to said implement, means for connecting said handle member to said implement for movement about two non-intersecting axes, one of said axes extending substantially perpendicularly to the direction of motion of said implement and in a substantially horizontal plane, the other of said axes being substantially normal to said first named axis and at an angle to the vertical, whereby a twisting motion of said handle about its own axis produces a change in the direction of motion of said implement, and selective means for locking said handle against movement about one of said axes.
6. Means for manually propelling and directing a surface traversing implement comprising an elongated handle member normally angularly inclined with respect to said implement, means for connecting said handle member to said implement for movement about two non-intersecting axes, one of said axes extending substantially perpendicularly to the direction of motion of said implement and in a substantially horizontal plane, the other of said axes being substantially normal to said first named axis and at an angle to the vertical, whereby a twisting motion of said handle about its own axis produces a change in the direction of motion of said implement, and selective means for locking said handle against movement about said second named axis.
7. Means for manually propelling and directing a surface traversing implement comprising an elongated handle member normally angularly inclined with respect to said implement, means for connecting said handle member to said implement for movement about two non-intersecting axes, one of said axes extending substantially perpendicularly to the direction of motion of said implement and in a substantially horizontal plane,

the other of said axes being substantially normal to said first named axis and at an angle to the vertical, whereby a twisting motion of said handle about its own axis in one direction or the other produces a corresponding change in the direction of motion of said implement, and selective means for locking the sections of said handle member to each other.

8. Means for manually propelling and directing a surface traversing implement comprising an elongated handle member normally angularly inclined with respect to said implement, means for connecting said handle member to said implement for movement about two non-intersecting axes, one of said axes extending substantially perpendicularly to the direction of motion of said implement and in a substantially horizontal plane, the other of said axes being substantially normal to said first named axis and at an angle to the vertical, whereby a twisting motion of said handle about its own axis in one direction or the other produces a corresponding change in the direction of motion of said implement, and means for limiting the extent of the rotatable movement of the sections of said handle member with respect to each other.

9. A floor tool comprising, a casing, supporting wheels for said casing, and an operating handle pivoted at one end to said casing on a horizontal axis and having a hand grip at its other end, said handle being formed from two sections sleeved to each other on an angle and having provisions to permit relative movement between the handle sections at their junction whereby the direction of movement of said casing may be changed by twisting the hand grip of said handle.

10. Means for manually propelling and directing a floor tool comprising an operating handle pivoted at one end to the tool on a horizontal axis and having a hand grip at its other end, said handle being formed from two sections sleeved to each other on an angle and having provisions for permitting relative rotational movement of the handle sections at the place where they are sleeved to each other whereby the direction faced by the tool may be changed by twisting the hand grip of the handle, and selective means for locking the sections of said handle to each other.

11. Means for manually propelling and directing a floor tool comprising an operating handle pivoted at one end to the tool on a horizontal axis and having a hand grip at its other end, said handle being formed from two sections sleeved to each other on an angle and having provisions for permitting relative rotational movement of the handle sections at the place where they are sleeved to each other whereby the direction faced by the tool may be changed by twisting the hand grip of the handle, and means for limiting the extent of the relative rotational movement of said handle sections with respect to each other.

12. A floor tool comprising, a casing, supporting wheels for said casing, a two-piece operating handle pivoted at one end to said casing on a horizontal axis and having a hand grip at its other end, means for rotatably connecting the two sections of said handle to each other on an angle normally lying in the plane defined by the axes of the handle sections, said means having provisions to permit relative movement between the handle sections at their junction whereby the direction of movement of said casing may be changed by twisting the hand grip of said handle.

13. A floor tool comprising, a casing, supporting wheels for said casing, a two-piece operating

- handle pivoted at one end to said casing on a horizontal axis and having a hand grip at its other end, means for rotatably connecting the two sections of said handle to each other on an angle normally lying in the plane defined by the axes of the handle sections, said means having provisions for permitting relative rotational movement of the handle sections at the place where they are connected to each other whereby the direction faced by the tool may be changed by twisting the hand grip of the handle, and selective means for locking the sections of said handle to each other.
14. A floor tool comprising, a casing, supporting wheels for said casing, a two-piece operating handle pivoted at one end to said casing on a horizontal axis and having a hand grip at its other end, means for rotatably connecting the two sections of said handle to each other on an angle normally lying in the plane defined by the axes of the handle sections, said means having provisions for permitting relative rotational movement of the handle sections at the place where they are connected to each other whereby the direction faced by the tool may be changed by twisting the hand grip of the handle, and means for limiting the extent of the relative rotational movement of said handle sections with respect to each other.
15. A device for steering the casing of an ambulant floor tool comprising a handle with a pair of sections arranged end-to-end connected at one end to the tool, coupling means for rotatably connecting the handle sections to each other on an angle at their contiguous ends so that a twisting movement of one part of the handle effects a twisting movement of the other part of the handle and thus steers the casing of the floor tool, the coupling means for said handle sections comprising a member having angularly disposed bearings for rotatably receiving the contiguous ends of the handle sections and means for operatively connecting the handle sections to each other.
16. A device for steering the casing of an ambulant floor tool comprising a handle with a pair of sections arranged end-to-end connected at one end to the tool, coupling means for rotatably connecting the handle sections to each other on an angle at their contiguous ends so that a twisting movement of one part of the handle effects a twisting movement of the other part of the handle and thus steers the casing of the floor tool, the coupling means for said handle sections comprising a member having angularly disposed bearings for rotatably receiving the contiguous ends of the handle sections and cooperating gears inside said member for operatively connecting the handle sections to each other.
17. A device for steering the casing of an ambulant floor tool comprising a handle with a pair of sections arranged end-to-end connected at one end to the tool, coupling means for rotatably connecting the handle sections to each other on an angle at their contiguous ends so that a twisting movement of one part of the handle effects a twisting movement of the other part of the handle and thus steers the casing of the floor tool, the coupling means for said handle sections comprising a member having angularly disposed bearings for rotatably receiving the contiguous ends of the handle sections, a pinion journaled inside said member and cooperating gears rigid with the contiguous ends of the handle sections and engaging said pinion for operatively connecting the handle sections to each other.
18. A steering handle for a manually propelled, wheel supported tool comprising upper and lower handle sections, a hand grip at one end of the handle, means for attaching the other end of the handle to the tool, and means for coupling the sections of said handle to each other on a substantially fixed angle to permit relative rotational movements of the handle sections for effecting the steering of the tool when the upper handle section is twisted about its axis.
19. A steering handle for a manually propelled, wheel supported tool comprising upper and lower handle sections, a hand grip at one end of the handle, means for pivotally attaching the other end of the handle to the tool, and means for coupling the sections of said handle to each other on a substantially fixed angle to permit relative rotational movements of the handle sections for effecting the steering of the tool when the upper handle section is twisted about its axis, the movements of one of said handle sections being about an axis inclined with respect to the axis of the other handle section.
20. A steering handle for a manually propelled, wheel supported tool comprising upper and lower handle sections, a hand grip at one end of the handle, means for attaching the other end of the handle to the tool, and means for coupling the sections of said handle to each other on a substantially fixed angle to permit relative rotational movements of the handle sections for effecting the steering of the tool when the upper handle section is twisted about its axis, said handle sections each being movable about an axis inclined with respect to the axis of the other handle section.
21. A sectional steering handle for a manually propelled, wheel supported tool comprising a bail and a shaft portion, a hand grip at one end of said shaft portion, means for attaching said bail to the tool, and means for coupling the bail to the shaft portion of said handle on an angle both with respect to the plane defined by the bail and the longitudinal axis of the shaft portion of the handle, said coupling permitting relative movement of the bail and shaft portion of said handle, whereby upon a twisting of the shaft portion of the handle the tool may be steered, the movement of the bail being about an axis inclined with respect to the longitudinal axis of the shaft portion of said handle and the movement of the shaft portion being about an axis inclined with respect to the plane defined by the bail of said handle.
22. A device for steering a wheel supported, ambulant floor tool comprising, a handle of sectional construction connected at one end to the tool and having an intermediate coupling member for rotatably connecting the end of one section of the handle on an angle to the end of another section of the handle, and means for gearing said handle sections to each other so that twisting movement of the handle section remote from the tool effects a turning or steering movement of the tool in a reverse direction.
23. A device for steering a wheel supported, ambulant floor tool comprising, a handle of sectional construction connected at one end to the tool and having an intermediate coupling member for rotatably receiving and connecting the end of one section of the handle on an angle to the end of another section of the handle, and means inside said coupling member for gearing the

contiguous ends of said handle sections to each other.

24. A device for steering a wheel supported, ambulant floor tool comprising, a handle of sectional construction connected at one end to the tool and having an intermediate coupling member for rotatably receiving and connecting the end of one section of the handle on an angle to the end of another section of the handle,

said coupling member including bearing portions for said handle sections disposed on an angle with respect to each other, means inside said coupling member for gearing the contiguous ends of said handle sections to each other, and stop means for limiting the movements of the handle sections with respect to each other.

JOHN J. McCABE.
ARTHUR W. SEYFRIED.
